A. J. HALL

FLOOR OR PLATFORM STRUCTURE

Filed Dec. 4, 1924

UNITED STATES PATENT OFFICE.

AKOS J. HALL, OF CLEVELAND, OHIO.

FLOOR OR PLATFORM STRUCTURE.

Application filed December 4, 1924. Serial No. 753,814.

My invention relates to floor structures generally and to stair platform structures particularly.

One of the objects of my invention is to 5 reduce the cost of production of floors and platforms.

Another object is to reduce the weight of floors and platforms.

Another object is to provide a floor or 10 platform which requires no bolts or rivets to connect the members thereof.

Another object is to form the metal floor with corrugations to stiffen this metal floor itself and by these corrugations form a mold 15 for ribs on the bottom of the poured floor, thereby also stiffening this poured floor.

Another object is to construct the metal parts of a floor or platform so that the entire structure can be assembled in the shop 20 and moved to the field and readily put into position with a minimum amount of field work.

Another object is to secure a platform to a supporting post in such a manner that the 25 platform can be shifted in relation to this post when the platform is installed.

Another object is to construct the metal floor in sections the sides of which do not touch each other and thereby not only eliminate close fitting of these sections but also 30 eliminate the cost of handling large sheets of metal and reduce the size and the cost of the dies for forming the floor.

Another object is to construct the middle 35 as well as the end sections of a sectional floor in duplicate, thereby reducing the cost of dies as well as permitting quantity production of these sections.

Another object is to construct the metal 40 floor of duplicate middle and end sections so that any number of these middle sections can be inserted to form any desired length of floor without change of dies.

Platforms, for stairs and the like, as well 45 as floors generally are extensively used and the cost thereof should be reduced to a minimum to benefit the public generally. The present invention aims to reduce to a minimum the cost of production of floors and platforms as well as the cost of installation thereof.

One embodiment of my invention is ill- 50 ustrated in the accompanying drawing as applied to a platform in which drawing:

Fig. 1 is a plan view of a platform embodying the features of my invention and

showing two stairs in dot and dash lines as related to the platform and also showing the frame structure and the joints thereof and the floor and the connections thereof to 60 the platform.

Fig. 2 is a section, taken on a vertical plane indicated by the line 2—2 in Fig. 1, showing the corrugated floor more clearly and the connection thereof to the end beams. 65

Fig. 3 is a section, taken on a vertical plane indicated by the line 3—3 in Fig. 1, showing more clearly the corrugated floor and the connections thereof to the longitudinal beams and the structure of the front 70 longitudinal beam and the carriers between the members of this beam.

Fig. 4 is a section through the supporting post and a portion of the platform, taken on a vertical plane indicated by the line 4 in Fig. 1, showing the clip to connect the platform to the post to permit the platform 75 to be shifted in relation to the post.

Fig. 5 is a sectional view of a portion of a 80 floor, similar to Fig. 2, showing a modification of the corrugations of the floor.

Similar reference characters refer to similar parts throughout the views.

The structure shown in the accompanying 85 drawing comprises, principally, the frame A, the metal floor B, the poured floor C, and the supporting post D.

The frame A is composed of two longitudinal beams 10 and 11 and two end beams 12 and 13. The beam 10 is the rear longitudinal beam while the beam 11 is the front longitudinal beam. 90

Each of the beams 12 and 13 is formed of channel section and the ends 14 thereof project beyond the longitudinal beam 10 to form an anchor in a wall. The webs of these end beams are provided with rectangular openings 15 for the beam 10 as will appear presently. The front end of these end beams is provided with the lugs 16 to engage the beam 11 as will appear presently. 95

The longitudinal beam 10 is formed of channel section and each end of the web thereof is provided with the rectangular lugs 17 which pass through the respective of the openings 15 in the webs of the end beams and are bent against the outside of these webs, thereby firmly securing the beam 10 to the end beams. The web of the beam 10 is provided with the rectangular openings 18 for the metal floor B as will appear presently. 100 105 110

The longitudinal beam 11 (front beam) is composed of the L shaped member 19 and the channel shaped member 20. The member 19 comprises the vertical leg 21 having the inwardly extending flange 22 and the horizontal leg 23 having the upwardly extending flange 24. This formation stiffens the member 19 considerably and requires the least amount of material, thereby reducing the weight of the platform. The vertical leg 21 is provided with the rectangular openings 25 and the lugs 16 of the end beams pass through these openings 25 and are bent against the inner surface of the leg 21, thereby firmly securing the end beams to the front beam 11. This leg 21 is also provided with the rectangular openings 26 for the metal floor B as will appear presently.

The lower flange 27 of the channel member 20 rests on the leg 23 and is secured thereto by the cleat bolts 28. The lower portion of the web of the member 20 abuts the flange 24.

In order to further stiffen the structure of the beam 11, the carriers 29 have the toe 30 thereof secured to the leg 21 by the cleat bolts 31 and have the end 32 resting on the top of the member 20. These carriers 29 take some of the load off of the bolts 28 and transmit it to the top of the member 20.

The structure of the end and longitudinal beams so far described comprises a substantial frame of sufficient stiffness and of minimum weight.

The member 20 may, conveniently, support the stringers G of the stairs E and F.

In structural work, where most of the punching and shearing is done in the shop and the erecting is done in the field, it is always found that considerable fitting is required when the parts are assembled in the field due to building or other conditions. In stair and platform structures, the supporting post is, usually, anchored in the ground or in a concrete floor and can not be located exactly in relation to the walls in which other portions of the platform are anchored; therefore, a fixed joint between the post and the platform, made in the shop, very seldom fits when it is attempted to install it in the building. In the present invention, all parts of the platform and all joints thereof can be prepared in the shop and brought into the field and assembled without any fitting and can be connected to the post readily because the platform can be moved in relation to the post and brought into desired position and secured to the post by merely tightening the clip hereafter described.

In the joint between the platform and the post, shown in Fig. 4, the member 20 passes through the opening 33 and the flange 27 thereof rests on the material of the post D. The clip 34 engages the front of the member 20 and extends back to the wall 35 of the

post and is secured thereto by the cleat bolts 36, thereby holding the web of the member 20 securely against the wall 37 of the opening 33. The wall 37 prevents the platform from moving forward and the clip 34 prevents it from moving backward. The openings 38 are provided in the post for the purpose of inserting a wrench to tighten the nuts on the bolts 36.

As to operation of the joint last described:—After the post D is fixed in position, the clip 34 is placed into the post and is loosely held therein by the bolts 36, the platform is then installed in relation to the walls surrounding the platform, and bolts 36 are then tightened up to lock the platform to the post; this arrangement permits the platform to be installed in relation to the walls around the platform and secured to the post in whatever position the post may be found.

The metal floor B comprises the middle sections 39, the end sections 40, and the cover plates 41. These sections and plates extend longitudinally between the beams 10 and 11 and are placed side by side to fill the space between the beams 12 and 13.

All of the middle sections 39 are duplicates and each is formed with the upper horizontal portion 42, the vertical portion 43, and the lower horizontal portions 44.

The ends 45 and 46 of each horizontal portion 42 extend over and rest on the upper flanges of the longitudinal beams 10 and 11 respectively.

One end of each portion 43 is provided with the lug 47 extending through the respective opening 18 in the beam 10 and is bent against the web thereof. The other end of each portion 43 is provided with the lug 48 extending through the respective opening 25 in the leg 21 of the beam 11 and is bent against the leg 21.

One end of each portion 44 is provided with the lug 49 extending through the respective opening 18 in the beam 10 and is bent against the web thereof. The other end of each portion 44 is provided with the lug 50 extending through the respective opening 25 in the leg 21 of the beam 11 and is bent against the leg 21.

Both end sections 40 are duplicates and each is formed with the upper horizontal portion 51 resting on the upper flanges of the beams 12 and 13, and with the vertical portion 52, and with the lower horizontal portion 53.

One end of each portion 53 is provided with the lug 54 extending through the respective opening 18 in the beam 10 and is bent against the web thereof. The other end of each portion 53 is provided with the lug 55 extending through the respective opening 25 in the leg 21 of the beam 11 and is bent against this leg.

All of the cover plates 41 are duplicates and the middle ones rest, primarily, on the lower horizontal portions 44 of the sections 39 and the two outer ones rest, primarily, on the lower horizontal portions 44 and 53. One end of each plate 41 is provided with the lug 56 extending through the respective opening 18 in the beam 10 and is bent against the web thereof. The other end of each plate 41 is provided with the lug 57 extending through the respective opening 25 in the leg 21 of the beam 11 and is bent against this leg.

It is observed that this floor structure not only materially helps to stiffen the frame structure but also provides a very stiff floor due to the corrugations formed by the formation of the sections. This formation of the floor requires no cross beams or other stiffening or supporting means because the floor itself is sufficiently stiff to carry the load usually applied to platforms.

This floor structure eliminates considerable material formerly found necessary for a safe platform and also reduces the number of parts in a platform. This reduction of material and reduction in the number of parts reduces the cost of material as well as the cost of production of the parts and also reduces the cost of assembling the parts since fewer parts are used; thereby reducing the cost of the platform.

Platforms of the character described are, usually, covered with a poured floor C such as concrete which is, usually, poured on top of the metal floor.

When the floor C is poured onto the metal floor B, some of the poured material fills the upper furrows 58 of the floor B and thereby forms transverse ribs on the bottom of the floor C which stiffen the same. When the floor C is so poured, some of the poured material also fills the hollow of the beam 11 and thereby forms a longitudinal rib on the bottom of the floor C which also stiffens the same.

In the floor structure shown and described, the floor C needs not be as heavy as a floor which has no ribs on the bottom; therefore, the present invention not only reduces the cost of the metal parts of the platform but also reduces the cost of the poured floor material and thereby reduces the cost of the platform still more.

I prefer to use cleat bolts with the nuts toward the inside so that the nuts are covered by the poured material and so that no one can tamper with the joints by turning the bolts from the outside. The main portion of the platform requires no bolts or rivets, but some bolts are necessary where the platform is attached to something connected with the platform.

Instead of disposing the vertical portions 43 and 52 at right angles to the hori-

zontal portions 42 and 51 as so far shown and described, it may be desirable in many instances to form the vertical portions 59 taper as shown in Fig. 5. This arrangement provides a stiffer floor C since the ribs 60 have a better mechanical proportion for strength. The bending of the plates to form the metal floor sections is also facilitated by this taper formation of the vertical portions of the floor B.

I am aware that modifications other than those pointed out may be made within the scope of the appended claims; therefore, without limiting myself to the precise construction and arrangement of elements shown and described and pointed out,

I claim:-

1. A structure of the character described, having, a frame having openings through some of the parts thereof, a plurality of floor sections primarily resting unsecuredly on said frame and spaced apart, each of said sections having lugs on the ends thereof and extending through some of said openings and bent against said frame, a cover plate primarily resting unsecuredly on the adjacent of said sections and bridging the space between adjacent sections, and each of said plates having lugs on the ends thereof and extending through some of said openings and bent against said frame.

2. A structure of the character described, comprising, a frame having openings through certain parts thereof, and a floor supported on said frame, said floor having individual metal floor sections spaced apart, each of said sections comprising a straight horizontal portion and depending portions and a horizontal flange on each of the depending portions, each of said straight horizontal portions projecting beyond the ends of said depending portions and resting on said frame, each of said depending portions having lugs extending through certain of said openings and bent against said frame, and a cover plate resting on said horizontal flanges of the adjacent of said floor sections and bridging the space between the adjacent of said floor sections.

3. In a structure of the character described, the combination of, a metal frame having openings through certain parts of the members thereof, and a floor supported on said frame, lugs on certain of said members and extending through certain of said openings and bent against said frame, said floor having individual metal floor sections spaced apart, each of said sections comprising a straight horizontal portion and depending portions and a horizontal flange on each of the depending portions, each of said straight portions projecting beyond the ends of said depending portions and resting on said frame, each of said depending portions having lugs extending through certain of

said openings and bent against said frame, and a cover plate resting on said horizontal flanges of the adjacent of the floor sections and bridging the space between the adjacent 5 of the floor sections.

4. A structure of the character described, having, a frame, a plurality of floor sections resting on said frame and spaced apart, a cover plate resting unsecuredly on the sides 10 of adjacent of said sections and bridging the space between adjacent sections, and said frame and said sections and said plates associated without being rigidly connected together.

15. 5. A structure of the character described, having, a frame, a plurality of floor sections associated with said frame and spaced apart on said frame, each of said sections having feet resting unsecuredly on said frame, each 20 of said sections having flanges on the longitudinal sides thereof, and a cover plate resting unsecuredly on said flanges of adjacent of said sections and bridging the space between adjacent sections.

25. 6. A structure of the character described, comprising, a frame composed of beams, at least one of said beams being hollow and comprising an L beam provided with stiffening flanges on the end of each leg thereof, a 30 channel beam secured to the horizontal leg

of said L beam, a plurality of carriers having one end thereof secured to said L beam and the other end thereof resting on said channel beam, a metal floor supported on said frame and one side thereof secured to 35 said L beam, and a poured floor on said metal floor and extending into said hollow beam to form a stiffening rib for the poured floor.

7. A structure of the character described comprising, a frame composed of beams, at 40 least one of said beams being hollow and comprising an L member provided with stiffening flanges on the end of each leg thereof, a channel member secured to the horizontal leg of said L member, a plurality of carriers 45 having one end thereof secured to said L member and the other end thereof resting on said channel member, a metal floor composed of individual corrugated sections spaced apart, one portion of each of said 50 sections supported on said L member, other portions of each of said sections supported on other members of said frame, a cover plate bridging the space between the adjacent of said sections, and a poured floor on 55 said metal floor and extending into said hollow beam and into the corrugations of the metal floor to form stiffening ribs for the poured floor.

AKOS J. HALL.
